UNITED STATES PATENT OFFICE.

BERNARR MACFADDEN, OF NEW YORK, N. Y.

HEATING OR COOLING AND HUMIDIFYING SYSTEM.

1,261,047.

Specification of Letters Patent.

Patented Apr. 2, 1918.

Application filed April 19, 1917. Serial No. 163,308.

To all whom it may concern:

Be it known that I, BERNARR MACFADDEN, a citizen of the United States, residing in New York city, in the county of New York 5 and State of New York, have invented certain new and useful Improvements in Heating or Cooling and Humidifying Systems, of which the following is a specification.

This invention relates to plants for heating or cooling, ventilating and humidifying the air of rooms, buildings, and the like, and has for its object to provide a unitary plant of this kind which can be at will adapted for either heating or cooling.

Another object is to provide a plant of this kind which is well adapted to be constructed in sizes from the smallest to the largest, and which will be very economical in operation for any size.

Another object of the invention is to provide an improved means for supplying a forced draft to the heating furnace.

Another object is to provide convenient means for recirculating and recooling or re-heating the air.

Another object is to provide automatic means for controlling the supply of water used for the humidifying process.

Another object is to provide suitable means for adapting a plant of the above kind for very quick heating.

Another object is to provide a simple plant of the above kind adapted for use with any kind of a heater.

These and other objects will appear as the description proceeds.

While herein I have described minute details of my apparatus, the invention is not limited to these, as the details of construction and combination may be greatly varied without departing from the spirit and scope of the invention as claimed.

In the accompanying drawing, the figure is a somewhat diagrammatic longitudinal 45 vertical sectional view showing, by way of example, one of many possible embodiments of the invention.

The apparatus as illustrated, comprises a heater 5, a heat exchanging flue 6, a heat 50 exchanging and humidifying cabinet and a conduit 8 for conducting the treated air from the cabinet to the rooms.

The heater 5 comprises a heater drum 9, provided with a water-jacket space 10. In 55 the lower part of the heater are disposed ordinary grate bars 11 and beneath them an

ash pit 12. In the middle part of the heater is disposed a partition 14 dividing the heater into a fuel reservoir 15 and a combustion chamber 16. Fuel is introduced into the 60 upper part of the fuel reservoir through the door 17; and the products of combustion pass out of the combustion chamber through the short stack 18.

The stack 18 is received in the lower open 65 end of the meandering heat-exchanging flue 6, and passes back and forth and finally out through the outlet flue 19 to the chimney, not shown. Resting upon the uppermost section 20 of the heat exchanging flue is the 70 heat exchanging and humidifying cabinet 7 which may be constructed of galvanized sheet iron or other suitable material, and is fed with air through the inlet conduit 21 either directly from the outside or by way 75 of the recirculation conduit 22 leading, for instance, from the rooms fed from the conduit 8. The cabinet 7 may be supplied with air either wholly or partly from either the outside or from the rooms, depending upon 80 the position of the dampers 24 and 25 in the conduits 21 and 22 respectively. When necessary or desirable, air may be forced through the cabinet 7 by means of the fan 25 disposed in the inlet conduit and driven 85 by any suitable motor 26.

When the apparatus is used for heating in its normal capacity, water from the hot water-jacket space 10 passes upwardly from the pipe 28 into the heat-exchanging coils 90 29 disposed in the sections of the heat-exchanging flue 6, and passes thence through the horizontal pipe 30 disposed in the bottom of the cabinet 7 and then through the heating or cooling coils 31 disposed near the 95 inlet end of the cabinet 7. From the coils 31 the water passes back down through the return pipe 32 to the lower part of the water-jacket space 10, thus completing the circuit of the water. It may be noticed that, 100 in the circuit just described, the up-going water must always be warmer than the down-flowing water, thus insuring a dependable flow in said circuit.

Instead of the heater 9 any ordinary 105 heater may be used. If this heater has not a water-jacket, the pipes 28 and 32 may be joined together by means of the valved connection 33 to complete the water circuit.

It is desirable that the air thus heated be 110 properly humidified; and to this end I have provided a vertical pipe 34 leading up from

the horizontal pipe 30 and feeding a branch pipe 35 provided with a horizontal, perforated portion 36 disposed along the upper part of the cabinet and adapted to let water 5 drip down upon the absorbent felts 37 carried upon horizontal groups of staggered horizontal bars 38 secured to the walls of the cabinet. These felts when thus moistened supply a sufficient quantity of moisture for 10 humidifying the air passing through the cabinet.

The lower part of the cabinet 7 forms a shallow tank for receiving the drip from the 15 perforated pipe 36, and this drip continues until the float 39 is raised a sufficient distance to cause the valve 40 to close off the access of water to the pipe 35 and the perforated portion 36. But when a part of the 20 water in the lower part of the cabinet becomes evaporated, the valve 40 will again open and feed water upon the felts 37 until the float 39 is again raised and the valve 40 again closed, thus automatically insuring sufficient water for supplying humidity to 25 the air.

When the operation thus described takes place the valves 41, 42, 43, 44, and 45 are closed and the valves 46, 47, 48 and 49 are opened. In order to compensate for the loss 30 of water in the system due to evaporation when the above operation takes place, water may be supplied through a supply pipe 50, in which case the valve 51 is then slightly opened. Alternately, water may be introduced from time to time through the pipe 35, the valve 51, the pipe 30 and the pipe 34 to the expansion tank not shown, to which the pipe 34 leads, in which case the valve 52 is left open and the water removed by 40 evaporation is replaced into the system from the expansion tank. When the expansion tank is not used the valve 52 may be closed.

When it is desired to use the plant only to a part of its capacity the water need not 45 be passed through the coils 31. In this case the valves 41, 42, 43, and 46 are opened, and the valves 44, 45, 47, and 48 are closed; and the water passes upwardly through the pipe 28, the coils 29 and through the valve 50 42, and is discharged into the lower part of the cabinet, where it gives up heat and moisture to the air and then passes out through the valve 41, the pipe 32 to the lower part of the water-jacket space 10. In order to 55 replace the water lost by evaporation, the valves 49 and 51 are left partly open and water passes up through the pipe 50, the pipe 31 through the lower part of the pipe 35, through the valve 43 and the nozzle pipe 60 53, and the spray nozzles 54 and drips into the cabinet. Since the evaporation of the water is gradual, the valve 40 never opens very wide and the water passing through the spray nozzles 54 is not in spray form but 65 merely trickles over the edge of the nozzle.

The pressure in the pipe 35 is not sufficient to force the water up to the horizontal position 36.

When it is desired to force the draft of the heater, the fan 25 is put into action, 70 whereby the air in the cabinet is somewhat compressed. Compressed air is then conducted down from the cabinet to the ash pit 12 through the draft-conduit 60, which communicates with said ash pit and an opening 75 61 in the side wall of the cabinet.

When it is not desired to use the forced draft, this opening is closed by means of the deflecting door 62 fixed on the rod 64, rotatable in the bearings 65, fixed to the wall 80 of the cabinet. This rod 64 continues upwardly and is provided with a manipulating crank 66 by which the deflected door may be opened to any desired angle. When this door is opened outwardly, for example to 85 an angle of 40°, it serves to deflect the air passing through the cabinet into the draft conduit 60. By adjusting this angle the amount of air permitted to pass through the conduit 60 is controlled.

When the plant is started and it is desirable to heat up quickly the water in the bottom of the cabinet, the hinged damper 67, between the lower and middle sections of the heat-exchanging flue 6 is opened, thus 95 permitting the products of combustion to pass directly from the stack 18 to the upper section 20 of said flue and thus heat the water in the lower part of the cabinet.

When it is desired to use this plant for 100 cooling a building or room, the fan 25 is started and the valves 44, 48, 43, and 51 are opened, and the valves 41, 42, 46, and 47 are closed. Water from the city supply then passes through the pipe 50, the valve 51, the pipe 68, the valve 44, through the pipe 32, the coils 31, the valve 48, the lower part of the pipe 34, the valve 43 to the spray nozzles 54, the valve 40 being fully opened, and the float 39 put out of action. The cold 105 water from the pipe 50 therefore cools the coils 31 and the air passing thereover, and then is sprayed from the nozzles 54 into the cabinet thus further cooling the air and filling the same with mist from the spray. 110 The air with the mist then passes between the felts 37, where the excessive moisture is absorbed by the felts, and then further evaporated as the air passes on, thus further cooling the air, which passes from the conduit 8 to the rooms. The air which is thus cooled may be drawn in through either the conduit 21 or the conduit 22 or partly 115 through both. The overflow from the lower part of the cabinet passes off through the 120 overflow pipe 69.

If it is desired to artificially cool the water passing in through the pipe 50, the valve 51 is closed and the valves 45 opened whereby the water passes through the cooling coils 125 130

70 of the ice box 71 and is cooled by the melting of the ice 72 in said box, thus effecting a lower cooling of the air passing through the cabinet 7.

5 I claim as my invention:

1. In a device of the character described, the combination of a heater, a heat exchanging flue leading from the heater; a cabinet resting upon said flue; and means for introducing water into the cabinet.

10 2. In a device of the character described, the combination of a heater; a meandering heat exchanging flue leading from the heater and having a substantially horizontal 15 upper section; a cabinet resting upon said upper section; and means for introducing water into the cabinet.

20 3. In a device of the character described, the combination of a heater; a heat exchanging flue leading from the heater; a cabinet resting upon the flue and adapted to receive heat therefrom; heating coils in said flue and communicating with said cabinet; means for passing air through said cabinet; 25 and means for introducing water into the cabinet.

20 4. In a device of the character described, the combination of a heater; a meandering heat exchanging flue receiving hot products 30 of combustion therefrom and comprising superposed sections; a cabinet upon the upper section; heat exchanging coils in the flue and communicating with the cabinet; means for at will causing said products of 35 combustion to pass through all of said sections or directly from the heater to the upper section; and means for introducing water into the cabinet.

40 5. In a device of the character described, the combination of a heater having a water-jacket; a heat exchanging flue receiving products of combustion from the heater; a cabinet resting upon said flue; heat exchanging coils in said cabinet; heat exchanging coils in said flue and communicating with said cabinet and said water jacket; and means for introducing water into the cabinet.

45 6. In a device of the character described, the combination of a heater having a water-jacket; a heat exchanging flue receiving products of combustion from the heater; a cabinet resting upon said flue; heat exchanging coils in said cabinet; heat exchanging coils in said flue and communicating with said water-jacket and said coils in the cabinet; and means for introducing water from said coils into the cabinet.

50 7. In a device of the character described, the combination of a heater having a water-jacket; a heat exchanging flue receiving products of combustion from the heater; a cabinet receiving heat from said flue; heat exchanging coils in said cabinet; heat exchanging coils in said flue communicating

with said water jacket and said coils in the cabinet; means for passing a draft of air through the cabinet; and means for introducing water from said coils into the cabinet.

70

8. In a device of the character described, the combination of a heater; a heat exchanging flue leading from the heater; a cabinet resting upon said flue; means for passing a current of air through said cabinet; means 75 for conducting air from said cabinet to rooms to be heated; a branching conduit leading to said cabinet and adapted to receive air either from said rooms or from the outside; and means for introducing 80 water into the cabinet.

9. In a device of the character described, the combination of a heater; a cabinet adapted to receive heat from the heater; means for passing a current of air through 85 said cabinet; means for conducting air from said cabinet to feed the draft of the heater; and means for introducing water into the cabinet.

10. In a device of the character described, the combination of a heater having an ash pit; a flue leading from the heater; a cabinet receiving heat from said flue; means for forcing air to pass through said cabinet; a draft conduit connecting the cabinet with 95 the ash pit; and means for introducing water into the cabinet.

11. In a device of the character described, the combination of a heater; a cabinet adapted to receive heat from the heater; means for passing a current of air through 100 the cabinet; a conduit adapted to conduct air from the cabinet to feed the draft of the heater; a deflector for deflecting air into said conduit; and means for introducing 105 heated water into the cabinet.

12. In a device of the character described, the combination of a heater having a water-jacket; a cabinet adapted to hold water in the lower part thereof; pipes connecting the 110 lower part of the cabinet with said water-jacket whereby a circulation of water may be established; and means for causing a current of air to pass through said cabinet.

13. In a device of the character described, the combination of a heater having a water-jacket; a cabinet adapted to hold water in its lower part; pipes connecting the lower part of the cabinet with the upper and lower parts of said water-jacket respectively; 120 means for passing a current of air through said cabinet, whereby the water is evaporated from the cabinet; and means for automatically replenishing the water in the cabinet.

125

14. In a device of the character described, the combination of a heater having a water jacket; a cabinet adapted to hold water in its lower part; pipes connecting the lower part of the cabinet with the upper and lower 130

parts of the water jacket respectively whereby a circuit is formed; a pipe for supplying water to the cabinet; a valve in said pipe; and a float adapted to float in the water of 5 the cabinet and operatively connected to said valve.

15. In a device of the character described, the combination of a heater adapted to heat water; a cabinet; a plurality of felts disposed across said cabinet; means for passing air through said cabinet and in contact with 10 said felts; and means for supplying water from the heater to said felts.

16. In a device of the character described, 15 the combination of a heater adapted to heat water; a cabinet; a plurality of felts disposed across said cabinet; means for passing air through said cabinet and in contact with said felts; and means for automatically 20 supplying water from the heater to said felts.

17. In a device of the character described, the combination of a cabinet; a plurality of coils in said cabinet; means for conducting 25 cold water to said coils; a nozzle connected to said coils and adapted to spray the water into the cabinet; and means for passing a current of air through said cabinet.

18. In a device of the character described, 30 the combination of a cabinet; a plurality of coils in said cabinet; means for conducting cold water to said coils; a nozzle connected to said coils and adapted to spray the water into the cabinet; means for passing a current 35 of air through said cabinet; and an overflow pipe leading from said cabinet.

19. In a device of the character described, the combination of a heater; a cabinet adapted to hold water in the lower part 40 thereof; coils in said cabinet; a cold water supply; and means for at will conducting hot water from the heater to said coils, or hot water from the heater to the lower part of the cabinet, or cold water from said supply to said coils.

20. In a device of the character described, the combination of a heater; a cabinet adapted to hold water in the lower part thereof; coils in said cabinet; a cold water supply; means for at will conducting hot water from the heater to said coils, or hot

water from the heater to the lower part of the cabinet, or cold water from said supply to said coils; and means for at will passing a current of air through the cabinet. 55

21. In a device of the character described, the combination of a hot water heater having a hot water jacket; a flue receiving the products of combustion from said heater; a cabinet resting upon said flue; an inlet conduit conducting air to said cabinet; a fan in the inlet conduit; an outlet conduit for conducting air away from the cabinet; a plurality of heating or cooling coils near the inlet end of the cabinet; a plurality of heat exchanging coils in said flue and connected in a series; a pipe connecting the lower end of said series to the upper part of said water jacket; a connecting pipe connecting the upper end of said series to one 60 end of said heating and cooling coils; a return pipe connecting the other end of said heating or cooling coils with the lower part of said water jacket; means communicating with said connecting pipe for discharging 65 water into the lower part of said cabinet; a pipe for supplying cold water to said connecting pipes; felts in said cabinet; a nozzle in said cabinet and adapted to spray 70 water upon said felts; pipes connecting said nozzle with said connecting pipe; valves in said pipes; a float connected to one of said valves; an overflow pipe leading from the lower part of the cabinet; means for discharging water from said return pipe into 75 the lower part of said cabinet; a pipe connecting said supply pipe to said return pipe; and valves for at will directing water to pass in a circuit from said water jacket through the coils in said flue through the 80 heating or cooling coils and back to the water jacket, or through said water jacket and the coils in said flue to the lower part of said cabinet and back to the water jacket, or from the cold water supply pipe through 85 said coils in the cabinet, through said nozzles, onto said felts and out at the overflow pipe. 90 95
